UNITED STATES PATENT OFFICE

2,583,195

AIR CONDITIONER

George Wilcox, Anna, Tex.

Application November 22, 1946, Serial No. 711,494

1 Claim. (Cl. 261—92)

1

The invention relates to an air cleaner, air cooler and air conditioning apparatus. The primary object of the invention is to provide an apparatus of this character which may be operated wholly within a room or enclosure, serving strictly as an air cleaner, by removing dust, lint, and other impurities from the air, and employing a non-evaporative liquid, therefore adding nothing to the air, for use in places such as coal mines, the grinding room of factories and the like.

Another object of the invention is to provide an apparatus of this character, which may be adapted for use in a furnace room in conjunction with a hot air furnace having several distribution ducts for air to carry heat to the various rooms of a building, said apparatus employing water as evaporative liquid to remove dust, lint and other impurities from and adds moisture to the cleaned air, which helps prevent furniture and woodwork from becoming dry and cracking and providing more comfortable and healthful air for occupants of the rooms. Said air conditioning apparatus increases volume of hot conditioned air by blowing into the cool air inlet of such hot air furnace.

In summer when no fire is in the furnace, said apparatus operates as an air conditioner, cooling air by evaporation, cleaning air of impurities and distributing air in the various rooms of enclosure through the furnace hot air system.

A further object of the invention is to provide an apparatus for use in districts with low humidity, for cooling, cleaning and moistening air within an enclosure. The apparatus is installed wholly outside of the enclosure, with the air outlet thereof attached to a window or other wall opening, the apparatus being effective to force warm stale air out of the enclosure by the introduction of fresh air which has been cooled, cleaned and moisturized while passing through the apparatus, thereby lowering the sensible temperature within said enclosure by evaporation of the liquid employed.

A still further object of the invention is to provide an apparatus of the character set forth having a tightly constructed housing of novel design with an air inlet and outlet at right angles to each other, having a fluid coupling torque driven revolving cylindrical filter pad washed by immersion in water as the filter rotates, the liquid level being predetermined and controlled by a float valve connected to the liquid supply under pressure.

A still further object of the invention is to 55 Opposite the opening 17 and embracing the dis-

2

provide an evaporative cooler, having a vanned driving member located outside or behind the air filter to reduce noise in operation and taking in air at atmospheric pressure, pushing the air through the apparatus thereby increasing the volume and efficiency above apparatus in general use.

A still further object of the invention is to provide an apparatus of this character having an air deflector of conical shape, located within the cylindrical filter, the cone pointing into the air stream and deflecting the air flow outwardly from the cylinder axis and through the filter pad, thus eliminating air pockets.

15 With the foregoing objects in view, the invention has further reference to certain features of accomplishment which will become apparent as the description proceeds, taken in connection with the accompanying drawings wherein:

20 Figure 1 is a rear perspective view of an evaporative cooling apparatus constructed according to the invention, partly broken away.

Figure 2 is an exploded view of the elements of the machine, from which has been omitted 25 the scroll housing.

Figure 3 is a front perspective view of the machine on a slightly reduced scale as compared to Figure 1.

Figure 4 is a perspective view similar to Figure 3 but showing the opposite end of the machine.

Figure 5 is a rear perspective view of the machine housing per se, shown in reduced scale as compared to Figure 1.

Figure 6 is a rear perspective view of the machine housing showing an end of the machine opposite to that shown in Figure 5.

Figure 7 is a fragmentary elevational view of the housing, in vertical section showing the float and valve.

40 Figure 8 is a detail perspective view of the access door closure of the housing, and

Figure 9 is a detail view of a combination overflow pipe and drain.

Continuing with a more detailed description of the drawing, reference numeral 10 denotes a scroll housing having a longitudinal air outlet 11 in one side and an air inlet 12 in one of the end plates 13. The inlet opening 12 is encircled by a reinforcing flange 14 which is affixed to the interior surface of the end plate, while exteriorly thereof, a fan housing 15 is secured to the end plate to embrace a fan 16. An access opening 17 is provided in the machine housing 10, to cover which is an arcuated plate 18 (Fig. 8).

charge opening of the housing 10 is a panel 19 whose opening 20 has a reticulated covering 21 through which air enters a room when emerging from the housing 10.

Rotatably arranged in the housing 10 is a cylindrical filter 22 of wood or glass fibers. The fibrous mat 22 is mounted on a foraminous cylindrical frame 23, the latter having a flange 24 at one end which is centrally supported on an axial shaft 25 by means of a radial series of arms 26. Disposed within the filter 22 is a coniform air deflector 27 whose apex is directed towards the inlet opening 12 of the housing 10 while its opposite end closes the end of the filter 22 opposite the inlet end of the housing.

The shaft 25 extends entirely through the filter and deflector 27, with one end journaled in a flanged bushing 28, affixed to the outside of an end plate 29, while the opposite end of the shaft is attached, through a coupling 29 to a driven member 30 (Fig. 2) emerging from a housing 31, containing a speed reducing gearing of conventional manufacture.

Mounted on the driving member 32 of the speed reducing gearing (Fig. 2) is a kinetically driven fan 33 which is adapted to impart motion to the filter 22 through influence of air propelled thereagainst by the fan 16, previously mentioned and which latter is driven by an electric motor 34. A member 35 (Fig. 1) affixed across the air inlet opening in one end of the machine provides a support for the gear housing 31 while the fan motor 34 is suspended by a bracket arm 36 depending in the circular fan housing 15.

In operation, the machine is installed to operate in a window, furnace room or any other place wherein it is desired to influence the temperature or humidity of the air and a source of water is connected to the float valve 36' (Fig. 7), and the motor is connected to a source of electrical supply, by means of a service line 37 (Figs. 3 and 4). Upon operating a switch 38, the motor is started to operate the fan 16 and the air influenced into the fan housing 15 thereby will impinge and set in motion the fan 33, the latter, in turn, driving the rotary filter 22 at a reduced speed, by virtue of the speed reducing gears in housing 31.

Water entering the housing 10 is controlled by the float 39 to maintain a predetermined level and adjacent this float is an overflow and drain pipe 40. The filter 22, in revolving, is continuously wetted by water in the bottom of the housing 10 in which the lower portion of the filter is submerged. As the air enters the open end of the filter 22, it is caused by the conical deflector 27 to flow outwardly through the filter in all directions and finally emerge from the housing through the outlet opening 20 devoid of entrained particles but sufficiently moistened to lower its temperature for the comfort of room occupants.

Manifestly, the construction as shown and described is capable of some modification and such modification as may be construed to fall within the scope and meaning of the appended claims is also considered to be within the spirit and intent of the invention.

I claim:

An air conditioner of the type described comprising in combination, a scroll housing having a vertical plate closing each end and a horizontal air outlet, the first of two of said end plates having a circular air inlet and embracing an intake fan housing attached exteriorly of said scroll housing, an axial shaft upon which is mounted an elongated coniform air deflector the base of which is attached and closes one end of a reticulated cylindrical filter frame, the apex of said deflector being directed into the airstream and terminating adjacent a series of divergent and radial arms attached thereto and supporting the open end of said filter frame, a filter mat attached thereto and covering the periphery of said filter frame, the filter assembly being rotatably mounted upon said axial shaft and being journaled in a bearing at one end in the second of two end plates of said scroll housing opposite said air inlet, a motor mounted in said intake fan housing, a fan on the shaft of said motor, a second fan mounted inwardly and independently of said first fan, said second fan mounted upon the input shaft of a parallel drive speed reducing gear box, said gear being supported by a crossmember attached to said first of two end plates and in turn journaling said axial shaft at the open end of said filter assembly, whereby air forced into said scroll housing by said first fan will impinge and by kinetic energy impart rotary motion to said second fan, the latter, in turn, driving the rotary filter, the air entering the open end of said filter assembly being deflected radially by the coniform deflector, for even passage through said filter, and float actuated means for maintaining a predetermined level of liquid in said scroll housing reservoir to bathe said filter mat as the latter rotates, and means for overflow and drainage of said tank.

GEORGE WILCOX.
